UNITED STATES PATENT OFFICE.

WILLIAM H. HALEY, OF FLOYD, IOWA.

MAIL-DELIVERING APPARATUS.

No. 834,798.

Specification of Letters Patent.

Patented Oct. 30, 1906.

Application filed August 8, 1906. Serial No. 329,765.

To all whom it may concern:

Be it known that I, WILLIAM H. HALEY, a citizen of the United States, residing at Floyd, in the county of Floyd and State of Iowa, have invented a new and useful Mail-Delivering Apparatus, of which the following is a specification.

This invention relates to a mail delivering and collecting system intended particularly for use in rural-free-delivery districts; and it relates specially to a system by which mail is distributed from a central point or post-office to outlying districts by self-propelled carriages set into operation by the postmaster and by which the mail is collected from such districts by being deposited in the carriages by the residents along the route and the carriages automatically returned after a delivery has been made.

The invention has for one of its objects to improve and simplify the construction and operation of systems of this character, so that the mail-carriages can be sent out over a route and automatically stopped at predetermined residences.

A further object of the invention is to provide a novel form of self-propelled carriage and a trap or cable along which the carriage travels, so that the system will be reliable and efficient in operation.

With these objects in view and others, as will appear as the nature of the invention is better understood, the invention comprises the various novel features of construction and arrangement of parts, which will be more fully described hereinafter and set forth with particularity in the claims appended hereto.

In the accompanying drawings, which illustrate one of the embodiments of the invention, Figure 1 represents a perspective view of one route of a delivery and collecting system, portions of the line being broken away. Fig. 2 is a side elevation of a self-propelled carriage shown adjacent one of the posts supporting the cable on which the carriage travels and the trolley-lines that supply the current to the motor. Fig. 3 is a front view thereof. Figs. 4 and 5 are plan views of two forms of hangers for the cable or line.

Corresponding parts in the several figures are indicated throughout by similar characters of reference.

In carrying out the invention a complete collecting and delivery system comprises a central station, such as a post-office, and a

plurality of independent routes radiating therefrom by which the incoming mail is distributed to the various residences and the outgoing mail collected. At the post-office a suitable source of electromotive force will be maintained to supply the motors with which the carriages are equipped. The several routes are practically the same in character, so that it has been deemed sufficient for an understanding of the invention to illustrate and describe one of them in detail.

Referring to the drawings, 1 designates a plurality of posts planted along a roadway, for instance, and supporting a single aerial cable or line 2, such line being broken away at places to indicate that it may be of any suitable length between the posts. The cable 2 is supported on the posts by means of hangers 3, that are preferably each constructed of a plate of metal 4, bent at one end in the form of a bracket for suitably securing it to the post. The outer end of the bracket is provided with a plurality of slits, so as to form fingers 5, as more clearly shown in Figs. 4 and 5, that are adapted to be alternately bent around the top and bottom of the cable. These fingers, as shown in Fig. 2, are shaped to conform closely to the circular cross-section of the wire or cable, so that the driving-wheels of the carriage can freely pass over the fingers without interruption. In order that the cable may follow closely the line of the road, special forms of hangers are necessary where angles occur in the cable, as shown at the third and fourth posts in Fig. 1. Where the cable makes an obtuse angle, as shown in Fig. 4, the outer edge of the hanger 4 is made convex, and where the cable makes an acute angle the outer edge of the hanger 95 is made concave, as shown in Fig. 5. At posts where the cable passes in a straight line the outer edge of the hanger where the fingers are formed will be, of course, straight.

Above the hangers 3 the posts are each provided with an arm 6, extending in the same direction as the hanger, for supporting separate trolley-lines 7 and 8, suitable insulating devices being employed for suspending the trolley-wires from the arms, as will be readily understood. At any suitable point on each post, preferably between the hanger 3 and arm 6, is secured a stop 9, projecting in the general direction of the hanger. These stops serve as abutments or devices for arresting the movement of the carriages, and the post at each residence is provided with

such a stop for bringing the carriage intended for that residence to rest. Beginning with the post at the residence nearest to the post-office the stop 9 is relatively short, and the 5 stops from this point to the terminal residence of the route are successively longer in length. These stops are adapted to engage with arms on the carriages, which arms are of varying length in a reverse order—that is 10 to say, the arm on the carriage intended for the first residence is relatively long and that on the carriage which travels to the terminal residence is comparatively short, so as not to interfere with the stops at any of the residences except the last, and the arms on the 15 carriages intended for the intermediate residences are of successively increasing length, beginning with that nearest to the station or post-office. It will thus be seen that the 20 several carriages are sent out from the post-office in a regular order, the carriage for the terminal residence being sent out first and that for the nearest residence being sent out last.

25 Each mail-carriage comprises a supporting-frame 10, having grooved wheels 11 arranged one above and the other below and in engagement with the cable 2. The journals 12 of the wheels are cushioned by springs 13, the 30 springs being under a tension for holding the wheels in engagement with the cable. By means of these springs the wheels can move toward or from each other, so as to accommodate themselves to varying thicknesses in 35 the cable and to permit the carriage to readily pass over the fingers 5 of the hangers. Suspended from the frame 10 is a mail-box 14, that is hung by means of two yoke-shaped arms 15, pivoted on the box and provided with eyes 16, which engage a hook 17 on the lower end of the carriage-frame. By 40 this arrangement the mail-box can be unhooked from the carriage for taking out or depositing the mail.

45 Any suitable motor mechanism may be employed for propelling the carriage. According to one method each carriage is provided with an electric motor 18, mounted at the upper end of the frame 10, and one or both 50 wheels 11 may be driven therefrom by means of belts 19 and pulleys 20, the latter being mounted on the shafts of the motor and driving-wheels 11. The motor is provided with suitable collecting devices 21 of 55 the underrun type which travel along the trolley-wires 7 and 8 to receive the current therefrom. The motor will be preferably so wound that the armature and field circuits will be independent. By this arrangement 60 the postmaster can by suitable controlling devices produce such combinations of circuits as to cause the motor to carry the mail out from the post-office and by other combinations reverse the motor for bringing the carriages back when the collection is to be taken.

For instance, by sending the current out through the wires 7 and 8 in the same direction and using the cable 2 as the return for the current the motors of the carriages will rotate in such a way as to deliver the mail to 70 the residences along the route. Then when it is desired to bring the carriages back the circuits can be so controlled that the current will pass from the post-office out through either one of the two lines 7 and 8 and return 75 by means of the cable 2 and the other one of the two trolley-wires. By this method the direction of rotation of the motors can be readily controlled to produce the proper direction of travel. While this specific arrangement may be desirable in some cases, I 80 do not wish to be limited thereto, since other arrangements and combinations may be employed to accomplish the same ends.

From the foregoing description, taken in 85 connection with the accompanying drawings, the advantages of the construction and method of operation will be readily appreciated by those skilled in the art to which the invention appertains.

I have described the principle of operation of the invention, together with the apparatus which I now consider to be the best embodiment thereof; but I desire to have it understood that the apparatus shown is merely 95 illustrative and that various changes may be made when desired as are within the scope of the invention.

What is claimed is—

1. In a mail delivery and collecting system, a plurality of posts extending along the route, a line strung along the posts, a plurality of carriages adapted to travel over the line, and devices on the posts and carriages for bringing the latter to rest in a definite order, said devices comprising stops on the posts projecting different distances therefrom, and means on each carriage arranged to engage its respective stop. 100

2. In a mail delivery and collecting system, a plurality of posts extending along a route, a line strung on the posts, and hangers for supporting the line on the posts, each hanger comprising a plate having integral fingers arranged to alternately engage on opposite sides of the line. 110

3. The combination of a post, a line, and a hanger for supporting the line on the post, said hanger comprising a plate having a curved edge and slit along the edge to form 120 fingers, said fingers being bent alternately over and under the line.

4. In a mail delivery and collecting system, a line, hangers therefor each comprising a member having fingers engaging around 125 the line, a carriage including wheels which are yieldingly urged toward each other for gripping the line and permitting them to separate to pass over the fingers of the hangers, a motor associated with the carriage for driv- 130

ing the wheels, a mail receptacle attached to the carriage, and means for supplying energy to the motor.

5. In a mail delivery and collecting system, the combination of a line, stops arranged at intervals along the line and disposed at different distances from a vertical plane passing through the line at the points adjacent the stops, a plurality of self-propelled carriages, and arms on the carriages which are of different lengths and arranged one on each carriage for engaging a definite stop to arrest travel in one direction and to permit the carriages to return in the opposite direction and to the point of starting.

15. In a mail delivery and collecting system, a single line, a plurality of carriages

adapted to travel back and forth between a station at one end of the line and residences or stations located at different points along the line, there being as many carriages as there are stations, a motor mounted on each carriage, devices arranged to cause the carriages to automatically stop at their respective stations, and means for supplying energy to the motors to convey the carriages to the stations and for returning them.

In testimony that I claim the foregoing as my own I have hereto affixed my signature in the presence of two witnesses.

WILLIAM H. HALEY.
